(57) **CLAIM**

The ornamental design for an assembling toy, as shown and described.

DESCRIPTION

FIG. 1 is a front view of an assembling toy of the present invention.

FIG. 2 is a rear view thereof.

FIG. 3 is a top plan view thereof.

FIG. 4 is a bottom plan view thereof.

FIG. 5 is a right side view thereof.

FIG. 6 is a left side view thereof.

FIG. 7 is a perspective view thereof.

FIG. 8 is a front view thereof with mouth in closed state.

FIG. 9 is a sectional view thereof taken along section line 9-9 of FIG. 6; and,

FIG. 10 is a sectional view thereof taken along section line 10-10 of FIG. 6.

The broken line showing of the assembling toy is for the purpose of illustrating portions of the article that forms no part of the claimed design. The dot-dash boundary line demarcates the boundary of the claimed area.
